US00D478945S

(12) **United States Design Patent** (10) Patent No.: **US D478,945 S**
Manville (45) Date of Patent: **** Aug. 26, 2003**

- (54) **CRAFT KIT CONSTRUCTION
COMPONENT—TRANSPARENT/
TRANSLUCENT, SINGLE-AXIS, CURVED
FORM WITH SERPENTINE EDGE**
- (75) Inventor: **Richard B. Manville**, Los Angeles, CA (US)
- (73) Assignee: **Mattel, Inc.**, El Segundo, CA (US)
- (**) Term: **14 Years**
- (21) Appl. No.: **29/157,985**
- (22) Filed: **Mar. 26, 2002**
- (51) LOC (7) Cl. **21-01**
- (52) U.S. Cl. **D21/484**
- (58) Field of Search .... D6/511; D20/22-28; D21/386, 390, 478-480, 484, 489-492, 496, 504, 505; 47/33; 273/156, 157 A, 157 R, 159; 446/85, 87, 102, 113
